UNITED STATES PATENT OFFICE.

GEORGE W. JACKSON, OF PHILADELPHIA, PENNSYLVANIA.

PROPELLER.

No. 866,365.

Specification of Letters Patent.

Patented Sept. 17, 1907.

Application filed January 31, 1907. Serial No. 365,006.

To all whom it may concern:

Be it known that I, GEORGE W. JACKSON, a citizen of the United States, residing in the city and county of Philadelphia, State of Pennsylvania, have invented 5 a new and useful Improvement in Propellers, of which the following is a specification.

My invention consists of an improvement in propellers, whereby the number of blades may be varied and set in different positions or spaces apart, and 10 means are provided for securing the blades to the hub in a firm and reliable manner.

It also consists of details of construction as will be hereinafter set forth and pointed out in the claims.

Figure 1 represents a perspective view of a propeller 15 embodying my invention. Fig. 2 represents a central longitudinal section thereof. Fig. 3 represents a face view of one of the blades detached. Fig. 4 represents a perspective view of the hub of the propeller.

Similar letters of reference indicate corresponding 20 parts in the figures.

Referring to the drawings: A designates a propeller shaft, and B designates the hub of the propeller mounted thereon.

C designates the blades of the propeller, the same 25 in the present case being three in number, of any suitable construction, excepting that the hub portions D of the blades have series of matched openings E arranged in circular form around the central opening or bore E', which latter receives said shaft A.

30 The hub B consists of the collar F and neck G, and is separate from the blades, said collar and neck having a bore to receive the propeller shaft. In the collar F are openings H which extend in the longitudinal direction of the same, and to the same are secured the 35 pins or studs J which project rearwardly therefrom parallel with said openings.

K designates screws or bolts, which are passed 40 through openings H in the hub, and corresponding openings E in the blades, it being noticed that the pins or studs J pass through other openings in said hub. On the rear ends of the bolts K, are the nuts L which are adapted to tighten against the hub portion of the adjacent blade, it being noticed that the several hub portions of the blades are placed one on the other on 45 the shaft and against the hub member and clamped together so that they are firmly connected with the hub B as one. The nuts and adjacent ends of the bolts are inclosed by the cap M, which is fitted on the end of the shaft A and covers said parts, its inner face 50 being somewhat recessed for that purpose, said cap in the present case being secured in position on the shaft by the key N which is inserted in the shaft or fastened in any other suitable manner.

It will be noticed that when the cap M is removed 55 and the nuts L are unscrewed, the blades may be fitted on the hub, it being seen that certain openings E

of the hub portions D of the blades receive corresponding pins or studs J, it being evident that the number of blades and their distances apart, or positions relatively to each other may be varied as desired. It will be 60 noticed also that the bolts K extend parallel with the studs J, and consequently with the openings H and E, thus avoiding the piercing of the peripheries of the hub portions D of the blades to receive securing bolts, which otherwise would weaken said peripheries and 65 provide projections thereon.

When a plurality of blades are employed, they are properly spaced apart and their hub portions placed one on the other on the shaft and against the hub member as has been stated, the relative openings thereof receiving the pins or studs J. Then the bolts K are passed through the openings H of the collar F and the other openings E of the hub portions D. The nuts L are then applied to the bolts and tightened thereon, whereby the blades are firmly connected with the hub and 75 prevented from displacement in either longitudinal or rotary directions. The cap M is also placed in position, whereby the nuts L are inclosed and concealed while being also prevented from being struck by objects in the water and loosened. 80

The bolts K have their heads sunk in the forward side of the collar F, whereby rotation of the same is prevented.

While I have specified certain means for carrying out my improvements, I do not wish to be limited 85 exactly to the same, but desire to make such changes as may come within the scope of the novelty involved, as for instance, two blades may be connected as one and having a single hub portion which is provided with a central opening to receive the propeller shaft, 90 and a series of openings around the same for the purposes of connection with the shaft, the same as shown in the single blade, Fig. 3.

Having thus described my invention, what I claim as new and desire to secure by Letters Patent, is:— 95

1. In a propeller, a blade having a hub portion, a hub member which is separate from said portion, said member and portion having each a central bore to receive a propeller shaft, and a series of openings surrounding said central bore, and separate devices for adjusting and securing 100 the blades on said member, said devices extending parallel through said portion and member.

2. In a propeller, a plurality of blades, each having a hub portion, a hub member from which the hub portions are separate, means on said portions and member for adjusting the blades, and separate means on said portions and member for clamping the same, said means being respectively parallel said hub member and the hub portions of the blades having each a bore to receive a propeller shaft. 105

3. In a propeller, a plurality of blades, a hub member and fastening devices, said blades being separable from said member and provided in their hub portions with central shaft-receiving openings, and matched openings surrounding the same, said hub member having a series 110 of projections adapted to occupy certain of said matched 115

openings, and openings to receive said fastening devices, which are also adapted to enter other openings of said blades.

4. A propeller composed of separable blades, and a hub member, said blades having hub portions provided with matched openings, projections on said hub member adapted to receive a respective number of the openings of said hub portions, fastening devices adapted to pass through said hub member and other openings in the hub portion, and means for tightening said devices.

5. In a propeller, a blade, and a hub member, said blade being separable from said member, a bolt passed through said member and the hub portion of said blade, a tightening device on said bolt, and a closure for said hub portion over the end of the tightening device thereof.

6. In a propeller, a blade, and a hub member, said blade being separate from said member, a securing bolt passing through said member and hub portion of said blade, a nut on said bolt, and a closure over said nut and adjacent end of the bolt, the same being adapted to be secured to the shaft of the propeller.

7. In a propeller, a blade having a hub portion, a hub member, which is separate from said portion, said member

and portion having central bores respectively to receive a propeller shaft, and openings between said bores and the peripheries of said parts, a stud projecting from the side of said hub member adapted to enter an opening in the hub portion, and a bolt adapted to be passed through another opening in said portion, said stud and bolt being adapted to extend in the direction of the length of the propeller shaft.

8. In a propeller shaft, a plurality of blades, each having a hub portion, a hub member which is separate from said portion, said portion and member having bores therein to receive a propeller shaft, and having a plurality of openings around said bore, a stud projecting from said member adapted to enter one of the openings of said hub portion, and a bolt adapted to pass through another opening of said hub portion, and a corresponding opening in the hub member, and means for tightening said bolts, said openings, stud and bolt extending in the direction of the length of the propeller shaft.

GEORGE W. JACKSON.
